UNITED STATES PATENT OFFICE.

MARY A. NICHOLS, OF BLOOMINGPORT, INDIANA.

DESIGN FOR A THREAD-CUTTER.

SPECIFICATION forming part of Design No. 32,819, dated June 12, 1900.

Application filed April 19, 1900. Serial No. 13,552. Term of patent 14 years.

To all whom it may concern:

Be it known that I, MARY A. NICHOLS, a citizen of the United States, residing at Bloomingport, in the county of Randolph and State 5 of Indiana, have invented and produced a new and original Design for Thread-Cutters, of which the following is a specification, reference being had to the accompanying drawings, forming part thereof.

Figure 1 is a plan or front view of my new design. Fig. 2 is a side view of my design.

The leading or material feature of my design consists of a thread-cutter having the shape, configuration, and ornamentation 15 shown in the drawings.

My design consists of a knife or cutter B,

with a guard C above, both being attached to a representation of a leaf and provided with a pin at the back for securing my design to the clothing.

Having described my invention, what I claim as new, and desire to secure by Letters Patent of the United States, is—

The design for a thread-cutter, as herein shown and described.

In testimony whereof I have signed my name to this specification in the presence of two subscribing witnesses.

MARY A. NICHOLS.
